FIG. 1

FIG. 2

FIG. 3

FIGURE 1 is a perspective view of a golfing aid located at a tee to provide visual information as to the characteristics of the hole, showing our new design.

FIGURE 2 is a rear elevational view;

FIGURE 3 is a side elevational view of the opposite side to that shown in FIGURE 1.

The essential features of the design reside in the full line portions of the drawing.

The support post is fragmentarily shown to indicate indeterminate length.

We claim:

The ornamental design for a golfing aid located at tee to provide visual information as to characteristics of hole, as shown and described.
